UNITED STATES PATENT OFFICE.

JOSEPH BERGER, OF NEW YORK, N. Y.

DESIGN FOR A CLOCK OR SIMILAR ARTICLE.

60,484.

Specification for Design.

Patented Feb. 28, 1922.

Application filed September 23, 1921. Serial No. 502,834. Term of patent 14 years.

To all whom it may concern:

Be it known that I, JOSEPH BERGER, a citizen of Russia, residing at No. 80 West 169th Street, in the borough of Manhattan, city, county, and State of New York, have invented a new, original, and ornamental Design for a Clock or Similar Article, of which the following is a specification, reference being had to the accompanying drawing, forming part thereof.

In the drawing Figure 1 is a front view, and Figure 2 is a side view of a clock or similar article of my new and improved design.

I claim:

The ornamental design for a clock or similar article, as shown.

JOSEPH BERGER.
